(57) **CLAIM**

The ornamental design for a portion of a pedal-based game controller, as shown and described.

DESCRIPTION

FIG. 1 is a front perspective view of the portion of a pedal-based game controller showing our new design;

FIG. 2 is a front view thereof;

FIG. 3 is a left view thereof;

FIG. 4 is a top view thereof; and,

FIG. 5 is a top view thereof.

The broken line showing of the remainder of the portion of a pedal-based game controller is for illustrative purposes only and forms no part of the claimed design.

1 Claim, 4 Drawing Sheets

FIG. 1

FIG. 2

FIG. 3

FIG. 4

FIG. 5
